GEORGE LAWRENCE ERTZ, OF NEW YORK, N. Y.

METHOD AND MEANS FOR VAPORIZING FUEL IN INTERNAL-COMBUSTION ENGINES.

Application filed August 25, 1921. Serial No. 495,275.

To all whom it may concern:

Be it known that I, GEORGE LAWRENCE ERTZ, a citizen of the United States and resident of New York, in the county of New York and State of New York, have invented certain new and useful Improvements in Methods and Means for Vaporizing Fuel in Internal-Combustion Engines, of which the following is a specification.

10 My invention relates to an improved method and means for vaporizing gasoline, heavy oils or alcohol fuels in the operation of internal combustion engines, and by the use of the heat generated by the same.

15 It is an object of my invention to vaporize the fuel, not only by the heat applied to the exterior of the containing vessel, but also by the heat applied internally to the fuel itself, the heat in both cases being derived from the

20 same source, which is the heated exhaust gases after the vaporized fuel has been mixed with air and burned in the engine cylinders.

It is also an object to provide auxiliary heating means whereby in very cold weather, such as zero weather, when very heavy oil, such as kerosene or the like, is being used there will be no trouble in vaporizing sufficient of the fuel to start the engine, prior to the automatic generation of vapor by the engine heat.

A further object is to provide simplified means for vaporizing the fuel whereby desired heat conditions may be quickly available for use.

Referring to the drawings, Fig. 1 is a view of an apparatus designed to be attached to an internal combustion engine.

Fig. 2 is a section along the line 2—2 of Fig. 1.

Fig. 3 is a section along the line 3—3 of Fig. 2.

In the drawings the same numerals indicate like parts.

1 represents the body of an internal combustion motor having exhaust pipe 2 and an inlet manifold 3. The engine as shown is illustrative of a typical four cylinder, four cycle engine, and the inlet manifold, as is usual, is a Y-shaped casting through the center of which extends a concentric, and preferably integrally cast pipe 4, leaving an annular space 5 between 4 and 3.

The entrance to pipe 4, which is exterior to manifold 3, is machined to receive a car-

buretor flange 6 to which is attached a carburetor 7 of any well known type.

The lower portion of manifold 3 is expanded into a bulb 8 on which are cast exterior radiating fins 9 and interior radiating fins 10. Exhaust pipe 2 is brought, preferably from the rear to the front of the engine, and extends in a curve, which is designed to bring it in conjunction with bulb 8, and pipe 2 has an expanded portion 11 which is adapted to encase bulb 8 in substantially gas tight relation.

Extending through the walls of 11 and 8 are insulating plugs 12 and 13 through which pass wires 14 and 15 joining up the ends 70 of a heating coil 16 made of a suitable resistance wire. Extending through the bottom of 11 and 8 is a draw-off cock 17, and in the bottom of 8 and adapted to open from the interior of 11 to the interior of 8 are 75 two more small drill holes 18 and 19.

The operation is as follows:

If it is assumed that wires 14 and 15 are connected to any convenient source of electric current supply, such as for instance the starting battery, the current is turned on and coil 16 rapidly attains a white heat. The engine is then cranked and the suction of the motor draws in a supply of fuel and air through carburetor 7 and pipe 4, at the same time a very minute amount of air is drawn in through the bulb 8 from the exhaust pipe 11 through the holes 18 and 19, which holes are preferably such as might be made with a No. 70 drill. The velocity of the air and gasoline, which is generally largely in an unvaporized condition, causes the liquid to be thrown against the red hot heating coil 16 thereby causing vaporization. At the same time the minute jets of air through 18 and 19, generally under high velocity, pick up the vaporized gasoline from the coil 16 and mingle with the balance of the air and thus the vapors and the air from both sources are drawn by the suction of the motor from the annular passage 5, manifold 3, into the engine cylinders.

The mixture is then fired and the exhaust gases pass out through the exhaust pipe 2 and on their passage to atmospheric discharge they heat up bulb 8 by contact therewith, which heating is greatly accelerated by the radiating fins 9 and 10.

It will be noted that after the first explosion of the motor the gases passing through

holes 18 and 19 will be devitalized or inert gases, consisting of the products of combustion and nitrogen, and carrying a large quantity of heat.

- 5 After a few revolutions of the motor under its own power, the supply of electric current to coil 16 is cut off, the heat generated by the exhaust gases and applied to bulb 8 being sufficient for the automatic and 10 continuous vaporization of any fuel deposited therein. Bulb 8 is designed for the purpose of trapping and vaporizing any fuel deposited therein from the carburetor and it is made with a contracted throat 20 15 for the purpose of giving an increased speed to the mixtures of air and vapor passing through to the motor from bulb 8. It is apparent that any fuel being delivered to the engine cylinders through pipe 4 from the 20 carburetor, owing to its velocity, will tend to pass through bulb 8 and strike the bottom thereof.

In the ordinary course of events in vaporizers of this type having similar construction, it is well known that the fuel is 25 by no means vaporized therein, due to the fact that the high boiling point fractions of the oil do not vaporize fast enough, and, secondly, accumulate in the bottom of the 30 bulb in increasing quantity until eventually the bulb is so filled with high boiling point fractions that the apparatus is inoperative. This is especially the case in cold climates where unless the bulb is heated externally by 35 a flame, or something of like character, the vaporizer is incapable of starting the engine.

In my method and apparatus I am able to overcome all these difficulties by providing for the continual agitation and vaporizing of the high boiling point fractions along 40 with the low boiling point fractions by admitting fine jets of superheated gases from the exhaust pipe to the interior of the vaporizer, where, responsive to the suction of 45 the engine, any fuel which has a tendency to collect on the bottom of the bulb is continually agitated, vaporized, and carried by the superheated gases to mix with the air coming from the carburetor and carried 50 therewith into the engine cylinder.

It has been repeatedly demonstrated and shown that by my method I am able to carry all the fuel in a vaporized condition into the engine cylinder, or, it may be seen that 55 with the construction of bulb 8 the fuel has no possibility of being drawn directly, in a solid condition, along with the air into the engine cylinder but must be deposited in bulb 8, and on repeated demonstrations after 60 different periods of running by opening cock 17 there will be no liquid fuel drawn off.

Also it has been shown by measurement that there is no crank case dilution due to 65 the fact of liquid fuel escaping past the pis-

ton rings into the crank case, thus proving the complete vaporization of the fuel.

The exterior radiating fins 9 serve to pick up the heat quickly from the exhaust gases and convey them by conduction to the interior fins 10 inside the bulb 8. Owing to the agitation and mixing of the liquid and gases in bulb 8, a continual spraying and vaporizing is taking place at the same time, the action of the gases causing the liquid to 75 be thrown onto the interior fins 10 whence by continuous refluxing they spread over a large heating surface and any of the high boiling point fractions unvaporized at one time will be caught at the bottom of the 80 bulb 8 by incoming jets of heated gases through holes 18 and 19 and thereby agitated, vaporized, and carried upwardly to the engine cylinder.

The arrows show the course of the air and 85 fuel from the carburetor to the manifold.

I am aware of different proposals to use a similar bulb as the one that I have shown but repeated experiments of this general 90 type have revealed to me the inherent defects as herein before explained but I am able to overcome these defects successfully by my proved method of introducing a superheated gas at the point of separation and 95 vaporization of the fuel and air.

It also appears that the velocity of the air from holes 18 and 19 is of great assistance in vaporizing a fuel under any conditions, but it is particularly efficient as applied by my method whereby deoxidized 100 gases are used, as by this method there is no effect on carburetor adjustment for different loads. At the same time under certain conditions I have found it advantageous to introduce air through cock 17, as well as 105 superheated gas through holes 18 and 19.

There are of course many variations of apparatus in the application of my method and I do not limit myself to the specific use as shown, as many other applications will 110 be apparent to those skilled in the art.

I claim:

1. The method of vaporizing liquid fuel for an internal combustion engine which consists in mixing fuel with air, segregating unvaporized portions of the fuel and then agitating the segregated portions without substantial atomization by passing therethrough a gas whereby the same are vaporized and again mixed with the air. 115

2. The method of vaporizing liquid fuel for an internal combustion engine which consists in passing a mixture of fuel and air to a container wherein unvaporized portions of the fuel are segregated, agitating said portions without substantial atomization by passing therethrough a heated gas whereby the same are vaporized and again 120 mixed with the air.

3. The method of vaporizing liquid fuel 125

- in a mixture of air and liquid fuel being conveyed to an internal combustion engine which consists in mixing pre-determined volumes of air and fuel in a carburetor and drawing same, responsive to engine suction, through a vaporizing chamber wherein unvaporized portions of the fuel are segregated, agitating the unvaporized fuel without substantial atomization by drawing therethrough part of the exhaust gas from the engine and thereby vaporizing the same and then conducting the vaporized fuel to again mix with the air.
4. The method of vaporizing liquid fuel in a mixture of air and liquid fuel being conveyed to an internal combustion engine which consists in passing a mixture of fuel and air to a chamber heated exteriorly by exhaust gases from the engine and wherein unvaporized portions of the fuel are segregated, agitating the unvaporized fuel by drawing therethrough a part of the exhaust gases and thereby vaporizing the fuel, without substantial atomization, and then conducting the vaporized fuel together with the part of the exhaust gases used for vaporizing to again mix with the air.
5. The method of vaporizing liquid fuel in a mixture of air and liquid fuel being conveyed to an internal combustion engine which consists in mixing fuel with air, segregating unvaporized portions of the fuel, and then agitating the unvaporized portions by drawing therethrough a heated gas and further air whereby the fuel is vaporized and mixed with first mentioned air.
6. An internal combustion engine having a cylinder, an inlet manifold, means to supply a mixture of fuel and air to the cylinder through the manifold, means to segregate unvaporized portions of the fuel in the manifold and means to introduce a gas into the segregating means whereby said unvaporized portions will be agitated without substantial atomization, vaporized and again mixed with the air.
7. An engine cylinder, an inlet manifold and an exhaust pipe therefor, a carburetor, in combination with means to pass a mixture of air and liquid fuel from the carburetor through the manifold to the cylinder whereby the unvaporized portions of the fuel are segregated, agitated without substantial atomization and vaporized by passing therethrough heated gases from the exhaust pipe, and then mixed again with the air together with said heated gases.
8. In combination, an engine cylinder, a carburetor, an exhaust pipe, an inlet mani-
- fold, said manifold having a dependent arm, 60 the lower portion of which is encased in the exhaust pipe wherein liquid fuel passing from the carburetor to the cylinder is segregated, and means to pass gases from the interior of the exhaust pipe to the interior of the lower portion of the manifold whereby the fuel is agitated and vaporized.
9. An interior combustion engine having an inlet manifold, a carburetor and an exhaust pipe attached thereto, in combination with means to segregate unvaporized portions of the fuel in the manifold and means to pass exhaust heated gases through said portions whereby the same are agitated without substantial atomization and vapor- 75
10. An inlet manifold for an internal combustion engine having an enlarged portion at its lower end designed to trap unvaporized fuel, an inlet passage for liquid fuel and air, an outlet passage for vaporized fuel and air, in combination with means to heat the enlarged portion exteriorly with exhaust gases from the engine and means to introduce part of the exhaust gases upwardly and through the trapped unvaporized fuel whereby the same is vaporized and directed to said outlet.
11. An internal combustion engine having an inlet manifold and an exhaust pipe attached thereto in combination with means to feed liquid fuel and air to the inlet manifold responsive to the engine suction, means to segregate unvaporized portions of the fuel in the manifold, electrical heating means to primarily vaporize the fuel, and means to continuously introduce heated gases, responsive to the engine suction, upwardly and through said segregated portion after the use of said electrical heating 95 means has been discontinued.
12. An internal combustion engine having an inlet manifold and an exhaust pipe attached thereto in combination with means to feed liquid fuel and air to the inlet manifold, means to segregate unvaporized portions of the fuel in the manifold, electrical heating means to primarily vaporize the fuel, means to continuously vaporize the segregated fuel by drawing heated gases 100 upwardly and means to introduce further air through the segregating means.
- Signed at Rochester, in the county of Monroe, and State of New York, this 15th 110 day of August, A. D. 1921.

GEORGE LAWRENCE ERTZ.
